UNITED STATES PATENT OFFICE

92,720

DESIGN FOR A LABORATORY BURNER BASE OR SIMILAR ARTICLE

Carl S. Hornberger, Glen Ellyn, Ill.

Application September 2, 1933, Serial No. 49,197

Term of patent 14 years

To all whom it may concern:

Be it known that I, CARL S. HORNBERGER, a citizen of the United States of America, and resident of Glen Ellyn, county of Du Page, and State of Illinois, have invented a new, original, and ornamental Design for a Laboratory Burner Base or Similar Article, of which the following is a specification, reference being had to the accompanying drawing, forming a part thereof, wherein

The figure represents a laboratory burner base embodying the design of this invention, the broken lines indicating a burner of the type which may be used with the base shown.

I claim:

The ornamental design for a laboratory burner base or similar article, substantially as shown and described.

CARL S. HORNBERGER.
